CLAIM

The ornamental design for an exercise bike, as shown and described.

DESCRIPTION

FIG. 1 is a first perspective view of an exercise bike showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 1.

The broken lines shown in the drawings depict portions of the exercise bike that form no part of the claimed design.

1 Claim, 10 Drawing Sheets
